4 Claims. (Cl. 250—40)

1

This invention relates to a radio-receiver which is adapted to be tuned in a continuous manner over a broad range of short waves and, moreover, can be tuned with band-spread control in at least two comparatively narrow bands of short-waves.

Tuning with band-spreading for obtaining a simple control of the receiving set is preferably effected by means of the same variable condenser designed for continuous tuning in other wave ranges, for instance, the said broad short-wave range.

To this end it has already come to be known to effect the band-spread control by connecting in the resonant circuit to be tuned two fixed condensers connected respectively in series with and in parallel with the variable condenser. In this case changing over from one comparatively narrow short-wave band to another is effected by replacing each of the two fixed condensers referred to by a fixed condenser having a different capacity. In order to ensure well reproducible tuning in the different narrow short-wave bands the said fixed condensers, and more particularly the fixed condensers to be connected in series with the variable condenser, must be of excellent quality, so that solely condensers of prime quality can be used for this purpose which, however, are comparatively expensive.

The present invention has for its object to eliminate at least partly this drawback.

According to the invention the same series- and parallel-capacity is used for tuning in the various comparatively narrow short wave bands and changing over from one comparatively narrow short-wave band to another is effected by varying the inductance of the resonant circuit.

Variation of the inductance is preferably effected by connecting one or more inductances in parallel with the inductance used for continuous tuning in the broad short-wave range.

The invention will be more fully explained by reference to the accompanying drawing, given by way of example.

In the sole figure the reference number 1 denotes a mixing tube to which are connected a pre-selection circuit 2 and an oscillator circuit 3. The anode-circuit of the mixing tube 1 is connected through a band-pass-filter 4, which is tuned to the intermediate frequency, to the intermediate-frequency amplifier, detector and low-frequency amplifier of the receiver which are schematically represented by 5.

Each of the circuits 2, 3 comprises a tuning condenser 10, 20 respectively and a coil 11, 21

2

respectively, the latter being coupled respectively with a coil 6 inserted in the antenna-circuit and with a back-coupling coil 7. For continuous tuning in a broad short-wave range the tuning condenser is connected directly in parallel with the corresponding coil in each of the circuits, as shown in the drawing.

For reception with band-spreading fixed condensers 13 and 23 respectively are connected in series and fixed condensers 14 and 24 respectively in parallel with the tuning condensers by changing over switches 12, 22, as a result of which the range of frequencies covered with maximum variation of the tuning condensers is limited to a great extent. At the same time an inductance 16, 17 or 18 and 26, 27 or 28 respectively is connected in parallel with the tuning coil 11 and 21 respectively by means of switches 15, 25.

Consequently the desired narrow short-wave band is chosen by connecting one of the coils 16, 17, 18 and 26, 27, 28 respectively in parallel with the coil 11 and 21 respectively used in continuous tuning which, if desired, may have connected in parallel with them trimmer condensers for readjustment of the minimum capacity of the resonant circuit.

Owing to the fact that short-wave coils, whose inductance depends only slightly on the ambient temperature, degree of humidity of the air and the like and in addition only very slightly alters in the long run, can be made in a more simple and consequently cheaper manner than condensers of much the same quality, the circuit according to the invention exhibits material advantages over the known circuit referred to above, in which changing over from one narrow short-wave band to another is effected by replacement of the condensers connected in series and in parallel with each tuning condenser.

Generally the back-coupling coil 7 can be coupled with the coil 21 of the oscillator circuit 3 used in continuous tuning in such manner that changing over of the back-coupling coil in reception with band-spreading, if the coils 26, 27, 28 are not coupled with the back-coupling coil 7, is superfluous. Of course, the same holds good for the less critical coupling between the antenna-coupling coil 6 and the coil 11 of the pre-selection circuit 2 used in continuous tuning.

When sharp pre-selection with band-spreading is not necessary the oscillator circuit 3 may be changed over, in the manner shown in the drawing, for tuning with band-spreading, more particularly when the receiver comprises a plu-

rality of pre-selection circuits, the pre-selection circuit 2 or one of the pre-selection circuits being tuned in a manner known per se, for instance by means of a fixed condenser, to the average frequency of the narrow short-wave band to be received.

In the executional example represented in the drawing only one coil is always connected in parallel with the coil used for continuous tuning to a narrow short-wave band. As an alternative, however, a plurality of coils may be connected in parallel with the coil used in continuous tuning in accordance with the desired narrow short-wave band.

Of course, the invention may also be used with advantage in receiving sets adapted to be tuned in a continuous manner in a plurality of broad short-wave ranges. In this case a saving in regard to the required inductances for band-spreading can still be obtained, by effecting the modification of the inductance in band-spreading in one broad short-wave range, by connecting together with the inductance used for continuous tuning in another broad short-wave range one or more other coils in series.

I claim:

1. A tunable circuit comprising a main inductance and a shunt variable condenser for tuning the circuit over a wide band of frequencies, and means for converting said circuit to one that is tunable by said variable condenser over a comparatively narrow frequency band, said means comprising a pair of condensers connected respectively in series and in shunt with said variable condenser and an inductance in shunt to the main inductance.

2. A tunable circuit comprising a main inductance and a shunt variable condenser which is varied through its range to tune the circuit over a wide band of frequencies, and means for effecting band-spread tuning of said circuit in a comparatively narrow frequency band utilizing the full range of said variable condenser, said means comprising a pair of condensers connected respectively in series and in shunt with said variable condenser and an inductance in shunt to the main inductance.

3. A tunable circuit comprising a main inductance and a shunt variable condenser which is varied through its range to tune the circuit over a wide band of frequencies, and means for effecting band-spread tuning of said circuit in a plurality of comparatively narrow frequency bands utilizing in each case substantially the full range of said variable condenser, said means comprising

a pair of condensers connected respectively in series and in shunt with said variable condenser, said series and shunt condensers being effective during the reception of each of said plurality of narrow frequency bands, and a plurality of inductances at least one of which is adapted to be connected in shunt to the main inductance during the reception of each of said plurality of narrow frequency bands.

- 10 5. A frequency converter system for super-heterodyne receivers including a signal frequency circuit and an oscillator circuit, each of said circuits comprising a main inductance and a shunt variable condenser, said condensers being uncontrolled and adapted upon variation through their range to tune the receiver over a wide band of frequencies, and means for effecting band-spread tuning of the receiver in a plurality of comparatively narrow frequency bands utilizing in each case substantially the full range of said variable condensers, said means comprising a pair of condensers connected respectively in series and in shunt with each of said variable condensers, said series and shunt condensers being effective during the reception of each of said plurality of narrow frequency bands, and a plurality of inductances at least one of which is adapted to be connected in shunt to each of said main inductances during the reception of each of said plurality of narrow frequency bands.
